T. TOKUHISA

COVER FOR GASOLINE TANKS

Filed Feb. 26, 1923

INVENTOR.
Tokusaburo Tokuhisa.

BY

Edward M. Kajima
ATTORNEY.

UNITED STATES PATENT OFFICE.

TOKUSABURO TOKUHISA, OF LOS ANGELES, CALIFORNIA.

COVER FOR GASOLINE TANKS.

Application filed February 26, 1923. Serial No. 621,302.

To all whom it may concern:

Be it known that I, TOKUSABURO TOKUHISA, a subject of the Emperor of Japan, residing in the city and county of Los Angeles and State of California, have invented a new and useful Cover for Gasoline Tanks, of which the following is a specification.

This invention has relation to an improved cover for gasoline tanks, and the like, and its objects are to provide a cover which may be quickly applied and removed for the refilling of the tank, and which, when removed, will not become lost, and which, when applied, will not jar loose; the invention being especially applicable to automobile tanks and radiators.

Other objects and advantages may appear in the subjoined detail description.

In the drawings, Figure 1 is a side elevation of my improved tank cover, Fig. 2 is a sectional view of the same. Fig. 3 is a perspective detail view of the valve disk and plunger. Fig. 4 is a perspective detail view of the nipple adapted to be attached to the tank opening. Fig. 5 is a sectional and plan view through the top part of the cap. Fig. 6 is a cross-section of the cap, with the levers removed therefrom. Fig. 7 is a fragmentary and sectional detail view of a modified form. Fig. 8 is a perspective detail view of a modified form having but one handle. Fig. 9 is a bottom plan view of the cap member shown in Fig. 8.

Referring to the drawings, in the embodiment of the invention shown, the nipple 11 is adapted to be screwed or otherwise secured in the tank opening; a portion of the tank 12 being shown. The nipple 11, has an inwardly projecting flange 13 which forms a seat for the valve disk 14, which has a metal gasket 15, preferably of soft copper for closing the valve on its seat, and a stem 16, for the disk, projecting upwardly and into the top chamber 17, of cap 18. A chain 19, is attached to the bottom of the disk 14, and provided on its extremity with a retaining member 20, which, when the cover is removed, remains inside of the tank and prevents the cap from becoming lost.

The nipple 11 has two oppositely disposed and projecting pins 21, adapted to engage with grooves 22, in cap 18. A spring 23, interposed between the valve disk 14 and partition wall 24, serves to normally press

the cap upwardly and thereby maintain the pins 21 in the end portion 25, of slots 22. To press the cap downwardly relative to the nipple, I provide levers 26, pivotally mounted on bearings 27, and having their inner extremities 28, in engagement with a bar 29, fixed to valve stem 16. On depressing levers 26, the cap is forced downwardly so that the pins 21 will enter the arcuate portion 30, of grooves 22. The cap, by means of levers 26 and handles 31, may be then rotated through a small arc, whereupon the pins 21 will pass through the part 32, of grooves 22, allowing the cap to be removed from the nipple. The chain 19 and anchor 20, then prevent the cap from becoming lost. To prevent a vacuum in the tank, I provide a minute opening 33, in the valve disk.

In the modified form shown in Fig. 7, I employ a single lever 34 for operating the valve and valve-stem. Other operative parts are similar to the preferred form.

In the modified form shown in Figs. 8 and 9, I employ a single valve operating lever 34, and a single handle 35 on the cap. Other operative parts are similar to the preferred form.

From the foregoing description and the drawings, it may be seen that I have provided a simple and efficient cover for automobile radiators and gasoline tanks, and the like, the device being instantly detachable for the purpose of refilling the tank or radiator, automatically locked against detachment when applied, and which will not become lost when detached. It is obvious that minor changes in the form and details of construction and arrangement of parts may be made in accordance with the appended claims without departing from the spirit of the invention or sacrificing any of its advantages.

What is claimed is:

1. In a quick-detachable tank cover, the combination with a nipple adapted to be secured to the tank opening, of projecting pins on opposite sides of the nipple, an annular flange projecting inwardly within the nipple and forming a valve seat, a cap for the nipple having integral arms, and grooves on the inner wall thereof adapted for engagement with the projecting pins on the nipple, a valve member within the nipple and an integral stem on the valve

100

member, levers pivotally mounted relative to the cap, a cross bar on the end of the valve stem, slotted extremities on the levers in engagement with the cross bar, a partition wall within the cap and beneath the cross bar, a spring interposed between the partition wall and the valve member, and a chain and anchor fixed to the bottom of the valve member and retaining the cap relative to the tank when detached from the nipple.

2. In a quick-detachable tank cover, the combination with a nipple fixed to the tank and having integral and opposed projecting pins, and an annular inwardly projecting valve seat flange, of a valve disk for engagement with the valve seat, a cap for the nipple having grooves in engagement with the nipple pins, a partition wall in the cap, a spring interposed between the partition wall and valve disk, a valve stem projecting through the partition wall, a cross bar on the extremity of the stem, levers pivotally mounted in the cap and projecting therefrom, slotted inner extremities on the levers in engagement with the cross bar, a chain fixed to the valve disk and extending into the tank, and an anchor on the end of the chain, adapted to remain in the tank when the cap is removed from the nipple.

3. In a quick-detachable tank cover, a tank nipple, a cap having a pin and groove connection with the nipple, a spring to force the cap upwardly, a valve in the nipple, a stem integral with the valve and projecting within the top of the cap, and levers pivotally mounted in the cap and in engagement with the top extremity of the valve stem.

4. In a quick-detachable tank cover, a tank nipple, a cap slideable and rotatable thereon and having grooves in its inner wall, opposed pins projecting from the nipple and in engagement with the grooves, a valve seat in the nipple, a valve to engage with the valve seat, a partition wall in the cap, a spring interposed between the valve and partition wall, levers pivotally connected to the cap and serving to depress the cap, and handles on the cap and extending beneath the levers.

5. In a quick-detachable tank cover, a tank nipple, a cap therefor, grooves on the inner face of the cap, pins on the nipple in engagement with the grooves, a valve in the nipple, a spring interposed between the valve and the cap, means for depressing the cap, handles for rotating the cap for disengagement when depressed, a chain fixed to the bottom of the valve, and an anchor fixed to the end of the chain and adapted to remain in the tank when the cap is removed from the nipple.

6. The combination with a tank nipple having opposed and projecting pins, of a cap for the nipple having grooves to receive the pins, a valve seated in the nipple, a valve stem for the valve and projecting from the top of the cap, a spring interposed between the valve and cap, ears on the cap, a lever pivotally mounted between the ears and having its extremity connected to the top of the valve stem, and a handle for the cap projecting beneath the lever.

In testimony whereof, I hereunto affix my signature.

TOKUSABURO TOKUHISA.
